AUTOMOBILE RADIO AERIAL ORNAMENT

Gerard Berozet, Toledo, Ohio, assignor to Gerard Industries, Toledo, Ohio, a corporation of Ohio

Application May 18, 1954, Serial No. 30,552

Term of patent 3½ years

(Cl. D14—6)

Figure 1 is side elevation of an automobile radio aerial ornament, showing my new design;

Figure 2 is a front end view of the ornament shown in Figure 1;

Figure 3 is a rear end view of the ornament, with the feather removed; and

Figure 4 is a top plan view of the ornament without the feather.

The fragmentary dotted line disclosure of an aerial is shown only for illustrative purposes.

I claim:

The ornamental design for an automobile radio aerial ornament, as shown and described.
